UNITED STATES PATENT OFFICE.

OBADIAH ALBERT ELMER, OF OGDENSBURG, NEW YORK.

PUNCH-PRESS SAFETY APPLIANCE.

Application filed December 21, 1921. Serial No. 523,953.

To all whom it may concern:

Be it known that I, OBADIAH ALBERT ELMER, a subject of the King of Great Britain, residing at Ogdensburg, in the county of Saint Lawrence, State of New York, have invented certain new and useful Improvements in Punch-Press Safety Appliances, of which the following is a specification.

10 This invention relates to attachments for presses of the power type, and the primary object of the invention is to provide an improved safety appliance for preventing the accidental operation of the press, thereby 15 eliminating any accident which might result from this contingency.

Another object of the invention is the provision of a novel means for engaging the operating rod of a foot treadle, so as 20 to prevent movement of the operating rod and the consequent actuation of the clutch mechanism of the press, when the foot treadle is inadvertently actuated by the operator of the press or persons passing by the 25 press.

A further object of the invention is the provision of an automatic safety device for power presses embodying a sliding latching bar, which is normally urged in the path of 30 an abutment carried by the treadle rod of the press, said latch being manually operated and disposed adjacent to the bed of the press, whereby the same can be conveniently actuated by the operator of the 35 press when the foot treadle is depressed.

A still further object of the invention is the provision of a novel safety appliance for power presses, which is adapted to be incorporated with an ordinary type of press, 40 requiring no change to the press structure or to the treadle operating means for the clutch, said safety appliance being of simple and durable construction and adapted to be built into the press at the time of manufacture thereof or connected with presses 45 already in use and on the market.

With these and other objects in view, the invention consists in the novel construction, arrangement and formation of parts, as will 50 be hereinafter more specifically described, claimed and illustrated in the accompanying drawings, forming a part of this specification, in which drawings:

Figure 1 is a fragmentary side elevation 55 of a press showing a part of the press mecha-

nism in section, illustrating the novel safety appliance connected therewith.

Figure 2 is a similar view showing the safety appliance in its actuated position and the foot treadle in its actuated position. 60

Figure 3 is an enlarged elevation of the improved safety appliance, showing the catch member associated with the treadle operating rod. 65

Figure 4 is a longitudinal section through the improved safety appliance, taken on the line 4-4 of Figure 3.

Figure 5 is an enlarged fragmentary elevation of a portion of the latching bar, showing the means of connecting the latching head therewith, a portion of the head being shown in section. 70

Figure 6 is an enlarged detail perspective view of the cross head carried by the operating rod for permitting the connection 75 of the contractile coil spring thereto.

Referring to the drawings in detail, wherein similar reference characters designate corresponding parts throughout the several views, the letter A indicates a press; 80 and B, the novel automatic safety appliance therefor.

The press A may be of the usual or any preferred type or character, but as shown the press is of the punch type, and includes the frame 10, the head 11 supporting the main drive shaft 12, the ram 13 which is operatively connected to the main drive shaft 12 and the bed 14. The drive shaft 12 has loosely mounted thereon the drive pulley 85 or fly wheel 15 which is adapted to be connected to the drive shaft through the medium of the clutch mechanism 16 by the treadle mechanism 17. The clutch member 16 and the treadle mechanism 17 is of the 90 ordinary or any preferred construction.

The treadle operating means 17 consists of the connecting treadle rod 24 which has its upper end pivotally connected to a swinging lever 25, which is pivoted as at 26 to the 100 head of the machine. This lever 25 is normally maintained in the path of the crank 21 carried by the clutch key 19 so as to prevent movement thereof under influence of the coil spring 22. The lower end of the 105 rod 24 is pivotally connected as at 27 to the ordinary type of treadle 28. It is obvious that when the treadle 28 is depressed the rod 24 will be moved therewith, swinging the lever 25 from below the lower end of 110

the crank 21, allowing the crank 21 to be 5 rotated under the influence of the spring 22 and moving the eccentric key 19 to its locking position in relation to the shaft 12 and the pulley wheel 15.

The improved attachment B includes a base plate 30 which can be connected to any preferred part of the press, by means of fastening elements 31. The base plate 30 is 10 provided at spaced points with guides 32, 33, and 34. These guides are disposed in longitudinal alignment and are adapted to slidably support the sliding latch bar 35, the outer end of which is provided with a hand 15 grip or handle 36. The base plate is preferably arranged on the machine in such a manner that the handle 36 will be disposed at a convenient point where an operator can readily grasp and actuate the same. The 20 inner end of the latch bar 35 carries the latch head 37, which may be made separate from the rod if so desired. An expansion spring 38 is coiled about the rod and engages the intermediate guide 33 and lock 25 nuts 39, which are threaded on the bar. The bar 35 adjacent to its outer end is also provided with threads for the reception of nuts 40, which serve as means for engaging the 30 opposite face of the guide 33 from the spring 38 in order to limit the inward movement of the rod under the influence of the spring 38. The lower forward end of the head 37 is bevelled as at 41 while its upper surface is 35 formed flat for a purpose which will be hereinafter more fully described. The inner end of the base plate 30 is provided with a transversely extending guide 45 forming tracks for the reception of a slide block 46. This slide block 46 is preferably formed 40 in two sections for clamping engagement with the treadle rod 24. The inner section of the slide block 46 which is designated by the numeral 47 is formed relatively large and is provided with guide flanges 48 for 45 engaging under the guide tracks and the outer section is formed relatively small and designated by the reference character 49 and is connected with the relatively large section 47 by suitable machine screws 50. 50 The meeting faces of the sections 47 and 49 are provided with polygonal shaped grooves 51 for the reception of the rod 24, and the portion of the rod which is disposed between the sections of the slide block 46 is 55 preferably formed polygonal shaped in cross section as indicated by the reference character 52. The block carries an inwardly extending nose 53 on its outer side edge, which is adapted to normally rest upon the head 37 of the latch bar 35, and downward movement of the treadle 28 and the rod 24 is prevented by said latch bar and nose. The upper surface of the nose 53 is inclined or bevelled as at 54 and upon upward movement of the rod 24, the inclined surface 54

of the nose 53 will engage the inclined surface 41 of the head 37 of the latch 35 and thus automatically force the latch bar back and allow the treadle to resume its normal position.

In use of the improved safety appliance, when it is desired to actuate the press, the handle 36 is grasped and the latch pulled outwardly and the treadle 28 depressed in the ordinary manner. This will move the 70 head 37 from out of the path of the nose 53 and allow the downward movement of the treadle and the swinging of the lever 25 out of the path of the crank 21. This will permit the actuation of the crank and the 75 eccentric key by the spring 22 and the driving connection between the fly wheel and the shaft will be established.

As soon as the treadle is operated, the latch is, of course, released, and upon the 80 stopping of the press, it is merely necessary to release the treadle 28, which will automatically return to its normal position under the influence of the contractile coil spring 55, which has its upper end connected to an 85 eye 56 carried by one edge of the base plate 30 and its lower end connected to an eye 57 90 formed on a block 58. This block 58 is mounted upon the treadle rod 24, and is held in adjusted position thereon by means of a 95 set screw 59. When the rod 24 resumes its normal position, the latch bar 35 will be automatically pushed inwardly owing to the formation of the nose 53 and the latch head 37 as heretobefore described. Upon the return movement of the treadle rod 24, the 100 lever 25 will again be disposed in the path of the crank 21 and thus move the crank to its normal position and stop the actuation 105 of the press.

From the foregoing, it can be seen that if the treadle is actuated inadvertently, in any way, the operation of the clutch mechanism 15 is absolutely precluded, and to permit the actuation of the press it is necessary to actuate the latch bar 35 as well as the treadle 28.

The device is of an exceptionally simple construction and can be readily incorporated with any type of press and so constructed and incorporated with the press in such a 110 manner that no loss of time is encountered by the operator of the press in actuating the latch bar.

Changes in details may be made without departing from the spirit or scope of this 115 invention; but,

I claim:

1. The combination with a power press including a frame, a bed, an operating shaft, a drive pulley wheel loosely mounted 120 upon the shaft, means for establishing driving connection between the drive pulley wheel and the shaft, a treadle mechanism for operating said means for establishing driving communication between the pulley 125 130

wheel and the shaft including a connecting rod, resilient means connected to said rod for normally urging the same in one direction, of a safety appliance for the press for 5 preventing the normal actuation of the treadle operating means including a base plate secured to the frame of the press adjacent to the bed, a latch bar slidably mounted on the base plate, a slide block adjacent to the rod, a guide mounted upon the base plate for receiving said slide block, an abutment formed on the slide block, spring means normally urging the latch bar into the path of the abutment for 10 preventing movement thereof in one direction, a hand grip formed on the outer end of the latch bar and disposed in relatively close relation to the bed.

15 2. As a new article of manufacture, a safety appliance for power presses comprising a base plate, longitudinally extending guides carried by the base plate, guide tracks carried by and extending transversely of the base plate adjacent to one end thereof, a sectional slide block carried by said guide tracks for adjustable clamping engagement with a connecting rod of the treadle mechanism of a press, an abutment formed on the slide block, a latch bar slidably carried by said guides, an operating handle formed on the outer end of the latch bar, a latch head formed on the inner end of the latch bar, spring means normally urging the head into engagement with the abutment for preventing movement of the abutment in 25 one direction in said guide tracks, the opposite faces of the abutment and latch head being bevelled.

30

OBADIAH ALBERT ELMER
